Primary Examiner — Mark A Goodwin*Assistant Examiner* — Benjamin M Weeks(74) *Attorney, Agent, or Firm* — Birch, Stewart, Kolasch & Birch, LLP(57) **CLAIM**

The ornamental design for a fixture for a frame of built-in home appliances, as shown and described.

DESCRIPTION

FIG. 1 is a front perspective view of the fixture for a frame of built-in home appliances showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear perspective view thereof;

FIG. 9 is a reference view showing the use state in which the claimed design is being attached to the frame for built-in home appliances; and,

FIG. 10 is a reference view showing the use state in which the claimed design has been attached to the frame for built-in home appliances.

The broken lines depict portions of the fixture for a frame of built-in home appliances that form no part of the claimed design. The portions of FIGS. 9 and 10 drawn in broken lines show environmental structure only and form no part of the claimed design.

1 Claim, 10 Drawing Sheets(56)
